United States Patent Office

Des. 211,685
Patented July 16, 1968

211,685

FISHERMAN'S KNOT TYING TOOL

George H. Hill, West Boxford, Mass.; Helen D. Hill,
executrix of George H. Hill, deceased

Filed Apr. 20, 1967, Ser. No. 6,774

Term of patent 14 years

(Cl. D22—31)

FIG. 1

FIG. 2

FIG. 3

FIG. 4

FIG. 1 is a front perspective view from one side of a fisherman's knot tying tool embodying my new design;

FIG. 2 is a view from one end thereof;

FIG. 3 is a view from the other end thereof; and

FIG. 4 is a perspective view from the other side thereof.

I claim:

The ornamental design for a fisherman's knot tying tool, substantially as shown.
